UNITED STATES PATENT OFFICE.

FREDERICK GOERTZ, OF NEWARK, NEW JERSEY, ASSIGNOR TO AUGUST GOERTZ & CO.,
A CORPORATION OF NEW JERSEY.

COMBINATION BAG FRAME AND VANITY OR POWDER BOX.

Application filed October 20, 1921. Serial No. 509,106.

To all whom it may concern:

Be it known that I, FREDERICK GOERTZ, a citizen of the United States, residing at Newark, in the county of Essex and State 5 of New Jersey, have invented certain new and useful Improvements in Combination Bag Frames and Vanity or Powder Boxes; and I do hereby declare the following to be a full, clear, and exact description of the 10 invention, such as will enable others skilled in the art to which it appertains to make and use the same, reference being had to the accompanying drawings, and to characters of reference marked thereon, which form a part 15 of this specification.

This invention relates, generally, to improvements in bag-frames, and more particularly to that class of hinged frame-sections which are used in the construction of 20 ladies' hand-bags, and the like; and, furthermore, to the provision of a vanity or powder-box, which is adapted to contain face-powder and a powder-puff, to the hinged frame-sections of the bag in a manner, that 25 the lid or cover of the vanity or powder-box can be opened without separating the two frame-sections, but when desired to get at the contents of the bag, that the two frame-sections of the bag may be brought into their 30 opened relation, without disturbing the relative position of the vanity or powder-box.

The present invention, therefore, has for its principal objects to provide:—

Firstly:—A bag-frame comprising a pair 35 of hinged or pivotally connected frame-sections, and a vanity or powder-box mounted to and carried by one of said frame-sections:

Secondly:—A bag-frame comprising a pair of hinged or pivotally connected frame-sections, and a vanity or powder-box mounted to and carried by one of said frame-sections, said vanity or powder-box being provided with a closing lid or cover which can be raised for getting at the contents of 45 the vanity or powder-box, without the necessity of separating or opening the frame-sections of the bag, but which will allow or permit of the two frame-sections of the bag also to be separated or opened, if so 50 desired.

Thirdly:—To provide in combination with the hinged frame-sections of a bag and a vanity or powder-box mounted to and carried by one of said frame-sections, a lock-

ing means or latch arranged in a manner 55 that said locking means or latch will at one and the same time maintain the closed or locked relation of both the said frame-sections, and of the lid or cover of the vanity or powder-box.

Fourthly:—To provide in combination with the hinged frame-sections of a bag and a vanity or powder-box mounted to and carried by one of said frame-sections, a horizontal relation of the powder-box to the 65 frame-sections, no matter whether the latter are in their closed or opened relation.

Fifthly:—To provide a vanity or powder-box having a closing lid or cover provided with a downwardly extending closing flange 70 adapted to enter into closing relation within the surrounding side-wall of the box, instead of about the outer surface-portions of the said side-wall, as heretofore.

And finally:—Other objects of the present 75 invention not at this time more particularly enumerated will be clearly understood from the following detailed description of the present invention.

With the various objects of the present 80 invention in view, the said invention consists, primarily, in the novel combined bag-frame and vanity or powder-box herein-after more fully set forth; and, the said invention consists, furthermore, in the novel 85 arrangements and combinations of the various devices and parts, as well as in the details of the construction of the said parts, all of which will be described in detail in the following specification, and then finally 90 embodied in the clauses of the claims, which are appended to and which form an essential part of the said specification.

The invention is illustrated in the accompanying drawings, in which:—

Figure 1 is a front elevation of a combined bag-frame and vanity or powder-box, showing one embodiment of the principles 95 of the present invention; and Figure 2 is a side edge-view of the same, looking in the direction of the arrow α in said Figure 1.

Figure 3 is a top or plan view of the combined bag-frame and vanity or powder-box; and Figure 4 is a bottom view of the same.

Figure 5 is a top or plan view of the combined bag-frame and vanity or powder-box, with the lid or cover of the vanity or powder-box shown in its opened position, said

view representing also in connection therewith, in dotted outline, the opened relation of the two frame-sections to one another; and Figure 6 is a transverse vertical sectional representation of the main portions of the combined bag-frame and vanity or powder-box, said section being taken on line 6—6 in said Figure 1, looking in the direction of the arrow *x*, and said view being 10 made on a slightly enlarged scale.

Similar characters of reference are employed in all of the said above described views, to indicate corresponding parts.

Referring now to the several figures of 15 the drawings, the reference-character 1 indicates a complete combined bag-frame and vanity or powder-box made according to and embodying the principles of the present invention, the same comprising two 20 main frame-sections 2 and 3, respectively provided at their free end-portions with registering pivot-lugs or ears, as 4 and 5, which are perforated in any usual manner, for the reception of suitable pivot-pins or 25 pintles 6. As shown, the two frame-sections 2 and 3 are respectively provided at their centrally disposed portions with outwardly and oppositely extending receiving members, as 7 and 8, each member being 30 preferably of semi-circular configuration, as here shown, although this is not necessary, it being possible to make said members of any other suitable and desirable configuration. As shown in the several figures 35 of the drawings, the member 7 comprises a lower portion 9, forming a part of the frame-section 2, from which extends in an upward direction, a vertical side wall 10, formed upon its outer surface with a marginal flange 11, and upon its inner surface with an inwardly projecting supporting flange 12. In a like manner, the member 8 40 comprises a lower portion 13, forming a part of the frame-section 3, from which extends in an upward direction, a vertical side-wall 14, formed upon its outer surface with a marginal flange 15, and upon its inner surface with an inwardly projecting supporting flange 16.

50 Suitably secured at its ends 18 to the frame section 3, by means of solder, or otherwise, is a supporting plate, as 17, upon which is mounted and suitably secured thereto, preferably by means of a rivet 19, 55 a box or shell 20, adapted to contain a powder-puff and face-powder, or the like. Connected with and extending from the upper portion of the member 8 are pintle-receiving ears or lugs 21 for the reception of a 60 pintle 22 upon which is pivotally mounted by means of an ear or lug 23 a suitably formed cover or lid-member, as 24. Suitably secured against the lower surface of the said cover or lid-member 24, preferably 65 by means of a rivet or pin 25, is a box-cover

26 bounded by a downwardly extending marginal closing flange 27, adapted when the several parts of the device are in their closed relation, to enter within the upper portion of the powder-receiving box or shell 70 20, so as to form a closure for the same, as will be clearly evident. Suitably disposed against the inner surface of said box-cover 26 there may be a mirror, as 28, suitably held in place by means of a suitably formed 75 retaining ring or frame 29, which is forced into frictional holding engagement with the inner surface-portions of the marginal closing flange 27, or may be otherwise secured thereto, as will be evident.

80 As shown, the upper end-portion of the above-mentioned rivet or pin 25, extends through the cover or lid-member 24, and above the outer or upper surface of the latter, to provide a lock-stud or post 30, for the purposes to be presently more fully set forth.

Connected with and extending from the member 7 are pintle-receiving ears or lugs 31 for the reception of a pintle 32 upon which is pivotally mounted by means of a perforated ear or lug 33 a suitably formed latch-bar or arm, as 34, which is provided near its free end-portion with a receiving hole or perforation 35, and a fingerpiece or knob 36, formed with a receiving socket 37, which is located directly over said hole or perforation 35, and serves to receive the said lock-stud or post 30, when the two frame-sections 2 and 3, and cover or lid-member 24 have been brought into their closed relation, when the said latch-bar or arm 34 has been forced into frictional holding or locked engagement with the said lock-stud or post 30, substantially as shown 100 in Figures 1, 2, 3 and 6 of the drawings.

105 As shown, the said frame-sections 2 and 3, and the portions 9 and 13 of the respective receiving members 7 and 8 are usually provided with thread-receiving holes or 110 perforations, as 38, for the sewing fast to the said members mentioned, of the usual bag-body; but, it will be clearly understood, however, that the said bag-body may be secured to the said members by means of 115 any other suitably constructed fastening devices.

120 The manner of operating the latch-bar or arm 34, for either raising the cover or lid-member 24, and the box-cover 26 connected therewith, to get at the contents of the vanity or powder-box, or for the purpose of separating the hinged frame-sections 2 and 3, to get at the contents of the bag will be clearly understood from the foregoing 125 description and from an inspection of the several figures of the drawings, and especially of Figures 5 and 6, and any further detailed description of the same is therefore 130 deemed unnecessary.

Of course, I am fully aware, that various changes may be made in the general arrangements and combinations of the several devices and parts, as well as in the details of the construction of the said parts, without departing from the scope of the present invention as set forth in the foregoing specification. Hence, I do not limit my present invention to the exact arrangements and combinations of the several devices and parts as described in the said specification, nor do I confine myself to the exact details of the construction of the said parts, as illustrated in the accompanying drawings.

15 It will also be understood that the surface- portions of the cover or lid-member 24, and of the two side-walls 10 and 14 may be suitably ornamented.

I claim:—

20 1. A bag-frame comprising a pair of hinged frame-sections, said frame-sections being formed with receiving members, a vanity or powder-box mounted in one of said receiving members and adapted to be embraced by the other receiving member, a cover or lid-member pivotally connected with said first-mentioned receiving member, and a locking means connected with the embracing receiving member for locking said frame-sections and said cover or lid-member in their closed relation.

25 2. A bag-frame comprising a pair of hinged frame-sections, said frame-sections being formed with receiving members, a vanity or powder-box mounted in one of said receiving members and adapted to be embraced by the other receiving member, a cover or lid-member pivotally connected with said first-mentioned receiving member, a lock-stud extending from said cover or lid-member, and a latch-bar pivotally connected with said embracing receiving member, said latch-bar being pivotally connected with said embracing receiving member, and said latch-

40 45 bar being provided with a receiving socket adapted to be brought into frictional holding engagement with said lock-stud for locking said frame-sections and said cover or lid-member in their closed relation.

50 3. A bag-frame comprising a pair of hinged frame-sections, said frame-sections being formed with receiving members, a supporting plate secured to one of said frame-sections, said plate extending across the receiving member of said frame-section, and a vanity or powder-box mounted upon and secured to said supporting plate, a portion of said vanity or powder-box being permanently embraced by the receiving member of

55 60 said last-mentioned frame-section, and another portion of said vanity or powder-box being adapted to be separably embraced by the receiving member of the other frame-section.

65 4. A bag-frame comprising a pair of

hinged frame-sections, said frame-sections being formed with receiving members, a supporting plate secured to one of said frame-sections, said plate extending across the receiving member of said frame-section, a vanity or powder-box mounted upon and secured to said supporting plate, a portion of said vanity or powder-box being permanently embraced by the receiving member of said last-mentioned frame-section, and another portion of said vanity or powder-box being adapted to be separably embraced by the receiving member of the other frame-section, a cover or lid-member pivotally connected with said first-mentioned receiving member, and a locking means connected with said second-mentioned receiving member for locking said frame-sections and said cover or lid-member in their closed relation.

5. A bag-frame comprising a pair of hinged frame-sections, said frame-sections being formed with receiving members, a supporting plate secured to one of said frame-sections, said plate extending across the receiving member of said frame-section, a vanity or powder-box mounted upon and secured to said supporting plate, a portion of said vanity or powder-box being permanently embraced by the receiving member of said last-mentioned frame-section, and another portion of said vanity or powder-box being adapted to be separably embraced by the receiving member of the other frame-section, a cover or lid-member pivotally connected with said first-mentioned receiving member, a lock-stud extending from said cover or lid-member, and a latch-bar pivotally connected with said second-mentioned receiving member, said latch-bar being provided with a receiving socket adapted to be brought into frictional holding engagement with said lock-stud for locking said frame-sections and said cover or lid-member in their closed relation.

6. A bag-frame comprising a pair of hinged frame-sections, said frame-sections being formed with receiving members, a vanity or powder-box mounted in one of said receiving members and adapted to be embraced by the other receiving member, a cover or lid-member pivotally connected with said first-mentioned receiving member, and a box-cover secured to the under surface of said cover or lid-member, said box-cover being provided with a closing flange adapted to enter within the upper portion of said vanity or powder-box.

7. A bag-frame comprising a pair of hinged frame-sections, said frame-sections being formed with receiving members, a vanity or powder-box mounted in one of said receiving members and adapted to be embraced by the other receiving member, a cover or lid-member pivotally connected with said first-mentioned receiving member,

- 4
1. A box-cover secured to the under surface of said cover or lid-member, said box-cover being provided with a closing flange adapted to enter within the upper portion of said vanity or powder-box, and a locking means connected with the embracing receiving member for locking said frame-sections and said cover or lid-member in their closed relation.
2. A bag-frame comprising a pair of hinged frame-sections, said frame-sections being formed with receiving members, a vanity or powder-box mounted in one of said receiving members and adapted to be embraced by the other receiving member, a cover or lid-member pivotally connected with said first-mentioned receiving member, a box-cover secured to the under surface of said cover or lid-member, said box-cover being provided with a closing flange adapted to enter within the upper portion of said vanity or powder-box, a lock-stud extending from said cover or lid-member, and a latch-plate pivotally connected with said embracing receiving member, said latch-plate being provided with a receiving socket adapted to be brought into frictional holding engagement with said lock-stud for locking said frame-sections and said cover or lid-member in their closed relation.
3. A bag-frame comprising a pair of hinged frame-sections, said frame-sections being formed with receiving members, a vanity or powder-box mounted in one of said receiving members and adapted to be embraced by the other receiving member, a cover or lid-member pivotally connected with said first-mentioned receiving member, a box-cover secured to the under surface of said cover or lid-member, said box-cover being provided with a closing flange adapted to enter within the upper portion of said vanity or powder-box, a lock-stud extending from said cover or lid-member, and a latch-plate pivotally connected with said embracing receiving member, said latch-plate being provided near its free end-portion with a lock-stud receiving perforation, and a fingerpiece-knob mounted upon said free end-portion of said latch-plate, said knob being provided with a receiving socket in alignment with the perforation in said latch-plate for the reception and the frictional holding engagement of said lock-stud therewith, so as to lock said frame-sections and said cover or lid-member in their closed relation.
4. The combination with the hinged frame-sections of a bag-frame, and a vanity or powder-box provided with a closing cover, of means connected with one of the frame-sections adapted to be brought into locking engagement with said cover for maintaining the closed relation of the clos-
- ing cover of the vanity or powder-box and also of the frame-sections.
5. The combination with the hinged frame-sections of a bag-frame, a vanity or powder box, and a hinged closing cover for said box, of a lock-stud extending from said cover, and a latch-plate hingedly connected with one of said frame-sections and adapted to be brought into separable holding engagement with said lock-stud for maintaining the closed relation of the closing cover of the vanity or powder-box and also of the frame-sections.
6. A bag-frame comprising a pair of hinged frame-sections, said frame-sections being provided with oppositely projecting and laterally extending members adapted when said frame-sections are closed to provide a receiving portion, and means connected with one of said laterally extending members for closing said receiving portion.
7. A bag-frame comprising a pair of hinged frame-sections, said frame-sections being provided with oppositely projecting and laterally extending members adapted when said frame-sections are closed to provide a receiving portion, means connected with one of said laterally extending members for closing said receiving portion, and a locking means connected with the other laterally extending member for locking the frame-sections in their closed relation.
8. A bag-frame comprising a pair of hinged frame-sections, said frame-sections being provided with oppositely projecting and laterally extending members adapted when said frame-sections are closed to provide a receiving portion, and a cover or lid-member pivotally connected with one of said laterally extending members for closing said receiving portion.
9. A bag-frame comprising a pair of hinged frame-sections, said frame-sections being provided with oppositely projecting and laterally extending members adapted when said frame-sections are closed to provide a receiving portion, a cover or lid-member pivotally connected with one of said laterally extending members for closing said receiving portion, a latch-plate pivotally connected with the other laterally extending member, and means connected with said cover or lid-member with which said latch-plate is adapted to be brought into separable holding engagement for locking the frame-sections in their closed relation.
10. In testimony that I claim the invention set forth above I have hereunto set my hand this 17th day of October, 1921.
